UNITED STATES PATENT OFFICE.

WILLIAM E. HARDACKER, OF MINNEAPOLIS, MINNESOTA, ASSIGNOR TO AMERICAN PLUMBING AND HEATING CO., OF MINNEAPOLIS, MINNESOTA, A CORPORATION OF MINNESOTA.

TRUCK.

Application filed December 8, 1923. Serial No. 679,411.

This invention relates to an improved truck which is useful for moving heavy radiators and heavy poles, pipes and other elongated objects. For example, it is the 5 present general practice in radiator handling installation to employ several laborers, usually four or five, to move radiators or radiator sections from the street or delivery space to the position in which the radiator 10 or section is to be installed. This invention provides a simple and convenient means for the movement of such objects by a single unskilled laborer. This selected embodiment of the invention includes upright members 15 which are mounted for movement upon suitable wheels, rollers, casters, etc. The upright members are spaced apart so that the radiator or other object to be lifted and transported will be straddled by the uprights. Horizontal members are carried adjacent the upper portion of the uprights and 20 preferably project laterally so that the flexible lifting means used will depend in spaced relation and may be secured to separate portions of the radiator so that it will be held 25 stable during truck-movement.

The object of the invention is to provide an improved truck.

Other objects of the invention will more 30 fully appear from the following description and the accompanying drawings and will be pointed out in the annexed claims.

In the drawings, there has been disclosed a structure designed to carry out the 35 objects of the invention but it is to be understood that the invention is not confined to the exact features shown as various changes may be made within the scope of the claims which follow.

40 In the drawings:

Figure 1 is a view in side elevation of the truck; and

Figure 2 is a view in end elevation and showing a lifted radiator in vertical section.

45 The structure shown is one more particularly adapted for use in handling radiators or radiator sections. There are provided a pair of spaced uprights 3 and 4 which are shown as integral at their upper end thus

forming an arched main frame. This main 50 frame is preferably of channel iron. The horizontal frame members 5 and 6 may also be of the same material and are preferably mounted in spaced relation and each is secured to one of the uprights. This fastening 55 is preferably effected by means of the rod 7 which extends across the space between the two horizontal members and is provided with terminally reduced threaded portions and project through the horizontal members and 60 the uprights and held in assembled position by means of the nuts 8. These horizontal members project from each side of the uprights adjacent the upper portions thereof. The truck is suitably mounted for movement, such for example, as by way of small 65 wheels 9 preferably with rubber tires 11. Two wheels are shown in the drawings as secured to each upright. A simple bearing for 70 such wheels is provided by the spaced bearing plates 12 and 13 which are arranged in adjacent spaced relation so that the lower ends of the uprights may be inserted therebetween and held by the bolts and nuts 14. The axles 15 of the wheels are suitably borne 75 at the opposite lower end portions of the bearing plates.

Reinforcing means connect the upright and horizontal members to reinforce the projecting portions of the latter. These reinforcing means are shown as spaced diagonal bars 16 of channel iron. These bars 16 are four in number and are arranged in pairs one extending from each end portion of the horizontal members diagonally downwardly 80 to the adjacent portions of the bearing plates 12 and 13, between which the lower ends are secured as by the bolts and nuts 17. The upper ends of each of the diagonal bars 16 are fastened to the adjacent end portions of 85 the projecting members. An effective fastening is achieved by means of the rods 18 which extend through aligned holes in the end portions of the horizontal members and their respective diagonal bars 16. The assembly 90 is secured by means of the nuts 19 secured to the threaded end portions of the rod on each side of the positioned horizontal and

diagonal members. A pair of handle-bars 21 may be secured to the upright members by means of the brackets 22, and an intermediate portion may be secured to its adjacent diagonal bar by means of the bolts and nuts 23.

The truck thus formed provides ample space intermediate the upright portions for the reception of objects even those which are much longer than the truck itself. Lifting means are provided upon the truck so that such objects may be lifted and held in suspended position whereby they will be carried when the truck is moved. A simple form of lifting means is provided by a flexible member operatively mounted on the truck and depending downwardly adjacent each side of the upright members in order to engage spaced portion of an object to be lifted whereby the object may be raised and held in suspended position. For this purpose, a shaft is rotatably mounted upon each of the projecting portions of the horizontal members. These shafts 24 are similarly mounted upon bearings 25, each having an integral depending block 26 to fit within the inwardly presented recesses of the horizontal channel-iron members. These blocks are held in position by means of the headed pairs of bolts 27. The flexible lifting means is here shown as a pair of chains 28, one each being adapted to be drawn over each shaft 24. While such chain may be mounted for simultaneous movement, in this embodiment of the invention, here shown as endless and as adapted to be placed around the shaft 24 and held by the pin 29 so that upon opposite rotative movement of the shaft, the chains will be wound about their respective shafts. The lower portions of the chains may be secured to or looped about an object to be lifted, such for example, as the radiator 31 shown in Figure 2, so that the radiator may be raised to the elevated position shown in such figure whereby upon movement of the truck, the radiator may be transported. The shafts 24 which are here shown as adapted for independent rotation may be turned by means of the crank 32 having a portion 33 adapted to be mounted upon the ends of the shafts 24 and to engage the pins 34 thereon, whereby the shafts may be manually rotated in order that the object can be held in suspended position, each shaft has a ratchet 35 fast thereto and is engaged by a pawl 36 pivotally mounted in operative position upon the adjacent horizontal frame members.

When used, for example with a radiator, the truck is pushed to a position straddling the radiator. The chains suspended from both of the windlasses or shafts 24, are then hitched about the radiator. The radiator is then hoisted into position by cranking each windlass. The crosspieces or rod between the horizontal carrier members act as stabilizers for the radiator and prevent any swinging or shifting of balance. This entire operation requires but a few moments time and may be handled by one man. With the radiator properly loaded the truck is wheeled to the desired point and the radiator deposited.

Having thus described my invention what I claim as new and desire to secure by Letters-Patent, is:

1. A device of the class described comprising a vertically elongated arched frame providing spaced legs, a pair of plates attached to each leg at the bottom in spaced relation, the plates extending in a direction perpendicular to the plane of the legs, a pair of wheels journaled between each pair of plates, having their rotative axes transversely of the plates, horizontal cross members attached to their mid portions one to each leg and extending in the same direction as the wheeled frame, brace members connecting at one end with the ends of the horizontal cross members and connecting at the opposite ends between the plates, and hoisting shafts journaled transversely of said cross members symmetrically at opposite sides of the frame.

2. A device of the class described, comprising a pair of parallel wheeled frames connected with respective legs of an elongated upright frame, arched at the upper end, horizontal cross members attached at their mid portions, one to each leg, adjacent the arched portion, and extending at right angles to the plane of the legs, hoisting shafts journaled transversely of said cross members, symmetrically at opposite sides of said frame, brace members connecting the outer ends of said cross members with said wheeled frames, and horizontal handles below the cross members, parallel therewith, connected at their inner ends to said legs and at an intermediate point to said brace members.

3. A device of the class described, comprising a pair of roller carrying frames, each comprising a pair of plates having a pair of rollers journaled therebetween, a channel iron bent to provide an elongated frame having an arched top and two vertical legs having their lower ends secured between the plates of respective roller frames, a pair of horizontal irons secured to said elongated frame adjacent the arched portion and extending at right angles to the plane of the legs, and hoisting shafts disposed transversely of said horizontal irons symmetrically at opposite sides of said arched frame parallel with the plane of the legs, and a pair of horizontal handles secured to said legs below said irons, secured terminally to the legs and intermediately to the braces.

4. A device of the class described comprising an arched frame providing spaced

legs, pairs of wheels for each leg having their axes substantially parallel with the plane of the legs, horizontal members secured to the legs and projecting from opposite sides in direction of truck movement, hoisting means arranged transversely between the horizontal members, braces connecting the horizontal

members and frame, and handles connecting with the braces and frame and extending in direction of truck movement.

10

In witness whereof, I have hereunto set my hand this 24th day of November 1923.

WILLIAM E. HARDACKER.
